MAKING SHOES WITH PLATFORMS AND COVERS

Nathan Waldman, Salem, Mass., assignor to
 United Shoe Machinery Corporation, Flemington, N. J., a corporation of New Jersey

Application June 2, 1945, Serial No. 597,215

1 Claim. (Cl. 12—142)

1

This invention relates to the manufacture of shoes having platform soles and covers therefor which are to be laid over the bottom face of the platforms prior to the attachment of outsoles thereto.

When, as in the manufacture of shoes of the slip-lasted type, it is desired to lay the platform cover over the platform and to attach it by means of pressure-sensitive cement applied to both the cover and the platform, the matters of the application of cement to these parts and the handling of the cemented parts during the making of the shoe are usually particularly time consuming and of such a nature that production on a satisfactory scale cannot be secured without running into the danger that too fast work will result in daubing cement upon the exposed surfaces of the shoe parts. If cement is accidentally applied to a point on the cover such that the latter becomes stuck to the edge of the platform sole, the cover must be drawn free from the sole before it can be pulled up tight and laid over the bottom face of the sole. It is important, therefore, to accurately limit the width of the margin of the cover which is coated so as to leave a clean margin where the cover will contact the periphery of the sole. The fact that slip-lasted shoes are relatively inexpensive makes it important to devise a procedure which will enable each operator to handle as many shoes in the course of a day as possible, to the end that production costs may be reduced.

A problem which arises in the making of such shoes results from the fact that it is necessary to allow the cement coatings on the surfaces of the two parts which are to be brought into contact to become tacky either by natural or by forced drying. Accordingly, if the procedure is such that these coatings must be dried separately, there is a very considerable waiting time between operations, thereby slowing the work and adding expense.

An important object of the invention is to provide an improved shoemaking procedure by the practice of which manufacturing costs may be reduced by speeding up production while, at the same time, danger of damage to shoes by reason or careless handling and poor workmanship may very largely be avoided.

The invention will best be understood from a consideration of the following specification taken in connection with the accompanying drawing, in which

Fig. 1 is a vertical section through a cementing machine and the forepart of a shoe being presented to this machine as the latter is being used

2

in applying a marginal band of cement to the platform cover of the shoe;

Fig. 2 shows the application of cement to the sock lining after completion of the operation shown in Fig. 1;

Fig. 3 shows a composite platform sole to the broad faces of which cement has been applied, ready for assembly with the shoe;

Fig. 4 shows the shoe with the platform spotted thereon and the cover turned;

Fig. 5 is a vertical, transverse section through the heel portion of such a shoe after the laying of the platform cover; and

Fig. 6 shows a completed shoe after an outsole has been attached thereto.

After shoe uppers such as that shown at 12 have been prepared, it is customary, in the manufacture of slip-lasted shoes, to attach to the bottom periphery of each upper a sole-shaped piece 20 of cloth 14, usually called a "sock lining," as by stitches 16 securing the margin of the sock lining to the margin of the upper. Either just before or just after this operation, one or more strips of cloth 18, 20 or similar material intended to be used for covering the periphery of the platform sole and known as the "platform cover" are also attached to the upper, as by stitches 24 securing an edge portion of the strip to the bottom edge of the upper with that surface of the cover strip which is to be exposed, in the finished shoe, lying against the outer surface of the upper. Such covers are frequently made of two pieces of cloth 18, 20 with their ends overlapping, as at 22, partly because of the different widths required at the forepart and heel and partly in order to avoid damage to the cover when turning it down. After these parts have been assembled, a last 10 is forced into the upper 12 to distend it and facilitate its handling. Upon so doing the sock lining 14 rest against the bottom of the last. Inasmuch as the lines of stitches 16 and 24 frequently are substantially coincident, no attempt has been made in the drawings to differentiate the two.

At this stage in the proceedings, a section through the forepart of the shoe on the last will show the cover 18 standing up around the body of the shoe upper 12, as in Figs. 1 and 2, which customarily will be provided with a lining 26. It is now desired to apply a band of cement to only the free or unattached marginal portion 28 of that face of the cover strips 18 and 20 which lies away from the shoe, and with a clean margin between the coated portion and the sides attached to the shoe. This clean margin will later cover

the edge face of the platform without adhering thereto. I have discovered that this can be done most expeditiously and with little danger of soiling the upper by performing the operation before the cover is turned because, then, the cover may be held slightly separated from the shoe without any stretching or straining of the cover material. This may conveniently be done by presenting successive portions of the cover to an upper-cementing machine of the type shown in Letters Patent of the United States No. 1,242,925, granted October 16, 1917, upon the application of J. W. Cosgrove. For this particular operation, the machine will preferably be modified by the provision of a thin work-supporting finger 30 carried on a pivoted arm 32. A spring 34 urges the finger 30 against the work to hold the latter in contact with an applying roll 36. The limit of movement of this finger 30 toward the roll is determined by a stop screw 38. Cement is supplied to the applying roll 36 from a reservoir 40 having a shut-off valve 42. While it will be understood that a machine such as that illustrated in Fig. 1 is not essential for the application of a band of cement of controlled width to the platform cover, it does offer a fast and clean method of accomplishing the desired result without danger of coating the upper of the shoe or of getting the coated portion stuck to the upper. Furthermore, the cover as thus applied to the shoe has sufficient stiffness or resistance to folding so that there is practically no danger that the coated margin 28 will come accidentally into contact with the sock lining 14.

It is then convenient, without waiting for the coating of cement on the margin 28 to become tacky, to apply to the sock lining 14, and if desired to the upstanding seam 44, such a coating of cement as may be necessary in order to hold the platform sole in position on the assembled shoe. This coating of the sock lining may be done in any convenient fashion, as, for example, by means of a hand brush 50, and the operator can conveniently support the shoe by grasping the cone of the last without contacting the fresh cement on the cover. Furthermore, the cover, in its position around the upper, does not interfere with the brush used in coating the sock lining.

In practice, it is found convenient to hasten the drying simultaneously of the two coatings of cement, by positioning the racks which support the coated shoes within a drying chamber of any convenient sort. During this drying period, a platform sole 52 (Fig. 3) has been coated on both broad faces in any desired fashion and, if desired, a wedge heel 54 has been attached to the sole by means of cement aided preferably by staples such as that at 56. The exposed surface 58 of this wedge heel is also provided with at least a marginal band of cement.

Since this platform-preparing operation may be carried on during the drying period for the coatings already applied to the shoe, a sufficient number of platform soles can be accumulated and dried so that they are ready for use as soon as the coatings previously applied to the cover and sock lining have dried sufficiently to become tacky. The platform sole is then spotted upon the shoe and the cover portions 18 and 20 are turned to the position alongside the periphery of the platform sole which is indicated in Fig. 4. The platform cover is then laid or "lasted" over the margin of the platform sole and of the wedge heel, if there is one, this being done either by hand or by machine in any suitable fashion. It will be understood that the portion 28 of the margin of the platform cover which is coated on the machine shown in Fig. 1 is substantially of the same width or slightly less than the width of that portion which projects beyond the surface of the platform sole when the cover has been turned as in Fig. 4 with a clean margin against the edge of the sole. This avoids any sticking of the cover to the edge face of the platform sole 52 and facilitates the cover-laying operation. After the platform cover has been laid, the shoe bottom may be completed by the application to it of an outsole 60 attached by cement in any usual fashion.

Having thus described my invention, what I claim as new and desire to secure by Letters Patent of the United States is:

The method of making shoes of the slip-lasted type, which consists in assembling a shoe upper, a sock lining and a platform cover by joining them around the lower peripheral edge of the upper, said cover overlying the upper and extending upwardly from the bottom of the shoe, inserting a last in the shoe, applying a coating of cement to the free marginal portion only of the outside of this upstanding cover which will overlie the bottom of the shoe, applying a coating of cement to the sock lining, drying said cement coatings substantially simultaneously, attaching a precoated platform sole, turning down the cover including the cemented marginal portion thereof and laying it over upon the bottom of the platform sole and attaching an outsole.

NATHAN WALDMAN.
